UNITED STATES PATENT OFFICE.

SHEDRICK M. HARDEN, OF CHICAGO, ILLINOIS.

TRAP FOR PREVENTING THE BURGLARIZING OF IRON SAFES.

No. 844,934.

Specification of Letters Patent.

Patented Feb. 19, 1907.

Application filed June 6, 1905. Serial No. 263,994.

To all whom it may concern:

Be it known that I, SHEDRICK M. HARDEN, a citizen of the United States, residing at Chicago, in the county of Cook and State 5 of Illinois, have invented new and useful Improvements in Safes, of which the following is a specification.

This invention relates to man-traps designed for use in connection with and to prevent the burglarization of safes, and has for its objects to produce a simple, inexpensive device of this character which may be readily installed, one whereby the burglar will be caught in an underlying compartment or trap which will effectually prevent his escape, and one wherein an alarm will be automatically sounded to give notice of the presence of the burglar in the trap.

With these and other objects in view the 20 invention consists in the construction and arrangement of parts, as will be hereinafter described, and particularly pointed out in the claim.

In the accompanying drawings, Figure 1 25 is a sectional elevation of an apparatus embodying my invention. Fig. 2 is a detail of the platform-locking means.

Referring to the drawings, 1 designates an apartment in which is located a safe 2 and 30 having an entrance-door 3 and a floor 4, there being provided beneath the floor a compartment 5, separated by vertical partitions 6 into a series of chambers or traps 7, in each of which latter there is arranged a downwardly-inclined chute or guard 8.

Included in and constituting a part of the floor 4 is a plurality of pivoted sections or trap-doors 9, arranged, respectively, over the underlying chambers or traps 7 and each 40 sustained by a central horizontal pintle or axle 10 and each provided at one end with a weight 11 and at its other end with a stop or abutment 12, the trap-doors being normally fixed against movement by means of longitudinally-movable locking members or bolts 45 13, designed for entrance into a socket 14, formed in the trap-door.

Sustained by springs 15 at the bottom of each of the compartments 7 is a depressible 50 member or platform 16, carrying a contact 17, adapted for coöperation with a contact 18 to complete a circuit through suitable

wires 19 to a bell or alarm 20, which latter may be situated in a station-house or the like, it being understood that the contacts 17 55 and 18 are normally out of contact and the circuit broken.

In practice the trap-doors 9 are arranged in a hall or passage-way leading to the safe 2, one of the doors being immediately in front 60 of the latter, and after closing the safe for the night the locking-bolts 13 are withdrawn to release the trap-doors, which latter are maintained in proper horizontal position through the medium of the weights 11 and 65 stops 12, as will be readily understood. Should a burglar enter the passage-way and step upon one of the trap-doors 9, the latter will be caused to swing on its pivot 10, thereby dropping the burglar into the under- 70 lying chamber or trap 7, it being understood that in falling he will be directed by the chute 8 onto the depressible member or platform 6, thus depressing the latter against the action of the spring 15 and through the 75 contacts 17 18 completing the circuit and sounding the alarm, it being understood that after dropping the burglar into the trap the door 9 swings into position, thus to prevent his escape. 80

Having thus described my invention, what I claim is—

A structure for preventing the burglarizing of safes comprising a floor of a room or hallway having openings therein, hinged 85 doors for closing the openings, means for locking the doors, a series of compartments arranged below the doors and divided by partition-walls, chutes secured to said walls having one of their portions vertical and the 90 other inclined, spring-platforms arranged in the bottom of said compartments in line with the inclined portion of said chutes, one of said platforms centrally pivoted to the partition between two of said compartments, and means for sounding an alarm when said platforms are depressed, substantially as specified. 95

In testimony whereof I affix my signature in presence of two witnesses.

SHEDRICK M. HARDEN.
